UNITED STATES PATENT OFFICE.

HARRY A. STEINMEYER AND JOHN H. VOSS, OF CHICAGO, ILLINOIS.

COOLING SYSTEM.

Application filed July 21, 1925. Serial No. 45,144.

The invention relates to vacuum systems and has for its main object to utilize a vacuum for the purpose of providing cooled, filtered and washed air in dining rooms, bed rooms or any other room of a dwelling or residence, in any room of a hotel or the like, in factories, railway coaches, Pullman-cars, or the like. In fact, the system, according to the present invention, may be used in any closed space wherever fresh, clean, cool air is desired.

A further object of the invention is to provide a place for storing vegetables and other perishable food stuffs without using either ice or any of the usual means for creating a cool or cold atmosphere, such as gas, ammonia, etc.

The store-room may be a room in a house, residence, hotel or the like, or may be a cabinet similar to an ice-box or refrigerator. The latter form may be used to an advantage in flats or the like, and in the accompanying drawings forming a part of this present application this form is shown as an example only, it being understood that other modifications may be used and alterations may be made, and the right is herein reserved to make such alterations and changes as fall properly in the scope of the appended claims defining the invention.

The drawings represent one embodiment of the invention.

In the drawing:

Fig. 1 is a front elevation of the cooling device in the form of a refrigerator;

Fig. 2 is an end view thereof;

Fig. 3 is a view similar to Fig. 1 on a larger scale, the front wall being removed and certain parts being broken away;

Fig. 4 is a vertical section approximately on the line 4--4 of Fig. 3;

Fig. 5 is a horizontal section substantially on line 5--5 of Fig. 3;

Fig. 6 is a fragmentary sectional view of the vacuum space containing the coil and the vacuum cells;

Fig. 7 is a vertical detail section through the ejector;

Fig. 8 is a vertical section through the intake valve for the air;

Fig. 9 is a vertical section through the outlet valve for the cooled and washed air;

Fig. 10 is a vertical section through the vacuum tank provided for cleaning purposes;

Fig. 11 is a vertical section through an outlet fixture for cooled and washed air.

The cooling device can be made in many different designs and modifications ranging from plainest and simplest to the finest and most elaborate designs and workmanship, but the principle of the apparatus consisting in extracting heat units out of the free air, transferring the low temperature produced thereby to the water cleaning the air and leading this cool purified air into the desired room always remains the same.

The path through which the air to be treated is conducted remains also always the same, as well as the treatment which the air undergoes while being led through said path.

The free air is moistened. The moistened air will be brought very rapidly to a temperature of between 50° and 40° Fahrenheit while being conducted through a cooling coil. This temperature will affect the water contained in the apparatus and utilized to purify the air. The air is then conducted to any desired room furnishing a cool, clean and agreeable ventilation.

At the same time the foodstuffs contained in the space designated therefor will be kept at a temperature of 50° to 40° Fahrenheit and will be surrounded by a vacuum. The space containing the foodstuffs does not need to be cooled by ice, because it is always surrounded by the cooled air.

In order to produce the apparatus at the lowest possible cost it must be made as light as possible. At the same time it must be strong enough to be able to resist the pressure exerted by the atmosphere upon creating the vacuum in the food container.

The food container 15 may be of any desired and suitable construction.

Adjacent the front edge of the side, top and bottom walls of the container angle irons 18 are provided which carry a soft rubber strip 19 surrounding the whole door opening of the container. A door 20 is hinged at 21 to the outer casing or cabinet 22. The container 16 is fastened to the cabinet in any convenient manner by any suitable means (not shown). The door car-

ries a lock with the bolts whereof it may be pressed tightly against the rubber strip 19.

A sheet metal box 38 is spaced from the container 15 so that a space is formed between these two elements. The sheet metal box is surrounded by a heat-insulating material 39, which fills the space between the box 38 and the inner surfaces of the cabinet 16 22.

In the space between the box and the container vacuum cells 40 are arranged. Three vacuum cells are provided, one in each of the spaces at the sides of the container and 15 one in the space in the rear thereof. Each vacuum cell is traversed by a plurality of pipes 41 and 42 which serve as stiffeners, so that the vacuum cell which is made of sheet metal will not collapse when the 20 vacuum is created in the cells. These cells are interconnected adjacent the tops and bottoms thereof by means of the narrow but high pipes 43.

At both sides of the vacuum cells cooling 25 pipe systems 44 are disposed. Each system consists of a plurality of pipes 45 of comparatively great diameter and a plurality of pipes 46 of comparatively small diameter. The pipes of each system are arranged 30 in such manner that a large diameter pipe alternates with a small diameter pipe. The pipes of each system are interconnected to form a coil, as clearly shown in Fig. 4. The coils are so arranged that the pipes 35 adjacent the vacuum cells will be of comparatively small diameter and will be connected with the adjacent greater pipe at the top thereof. The two small pipes adjacent each vacuum cell are connected at their lower ends by means of a perforated pipe portion 47 penetrating the adjacent vacuum cell.

The space between the walls of the metal box 38 and the container 15 for the food-stuff is filled with water up to the water 45 mark 48 (Fig. 2). In order to facilitate the observation of the water level a water gauge 49 is provided.

An electrometer 50 is arranged in the 50 lower portion of the cabinet 22 underneath the container and the box surrounding the same. It is, however, to be noted, that the motor may be positioned at any convenient place as long as it is in driving relation with a pump.

55 At one side (left hand in Fig. 3) the walls 16 and 38 of the food container and the box extend downwardly beyond the bottoms of the said elements and form a chamber 52 which is the lowest portion of the water 60 chamber receiving the vacuum cells and the cooling pipe systems. In order to fill the water chamber a funnel 53 containing a filter screen 54 is provided and a cock 55 serves to drain the chamber, when it is desired to 65 change the water therein. It is, however, to

be understood that a direct connection may be had with a water and sewer system to fill and drain said water chamber.

The intake bore 56 of the pump 51, which is preferably of the rotary type, communicates with the extension chamber 52. The outlet pipe 57 of the pump contains the ejector 58 which may be of any suitable and known construction. Preferably the outlet pipe and ejector are arranged inside of the 75 vacuum cell 40 arranged at the rear of the food container. The water will be forced with great velocity through the ejector and will thereby exhaust the air in the vacuum cell. The adjacent cooling coils extend, as 80 stated above, through the vacuum cell with the perforated pipe portion 47. This pipe portion is covered by water and the suction of the ejector will cause the air in the coil and some of the water to follow the upwardly directed current of water in pipe 57. The top of this pipe is covered by a perforated plate 59 through the perforations 85 whereof the mixture of air and water will be ejected. As also stated above, all vacuum cells 40 are interconnected by means of the flat pipes 43, so that the action of the one ejector 58 will affect all vacuum cells and all cooling coils. By means of the suction 90 created by the ejector in the coils fresh air 95 will be drawn into the coils and the path for this free air is as follows:

Outside of the house an outside air intake 60 is provided in any suitable place. From there a pipe 61 leads to an air intake valve 62 on the cabinet, and the pipe 63 leads to the fresh air distributor 64. This distributor is connected with the cooling systems by means of the connecting pipes 65. From the pump 51 the usual vent pipe 66 leads to the distributor and is used in this case to conduct water to the distributor into which the vent pipe reaches with a perforated pipe portion 67. A sponge 68 may be inserted in the distributor in order to retain some of the 110 moisture.

A pipe 70 for cool air leads from the container to the outside of the cabinet and connects there with an outlet valve 71. From there the cool air passes through a distributing pipe 72 which may lead to the different rooms of the house which are intended to be cooled, and in each room will be provided a branch pipe 73 leading to the cooling fixture 74. The intake valve 62 and the outlet 115 valve 71 are connected by means of a connecting pipe 75 which terminates in an opening 76 in the valve 62, and the opening 77 in the valve 71. The intake valve has a valve cone 79 which is pressed on its seat by a 120 spring 78. The tension of this spring may be adjusted by means of an adjustable screw 80. The outlet valve is constructed similarly, but it has an upper valve cone 81 and the lower valve cone 82. The upper valve cone 125 130

is pressed onto its seat by the spring 83, and the lower one by a spring 84. The last named spring rests in a bore of an adjusting cap 85, and on the top of the valve a screw 86 is provided which limits the receding movement of the cone valve 81. The connection between the two valves serves the following purpose: If too much cold air should pass through the outlet pipe 70, the pressure on the valve cone 81 will be transferred by means of the spring 83 to the valve cone 82 so that the last named valve cone will be unseated and the cold air which is not intended for direct use may then pass through the opening 77 in the valve 71, through the connecting pipe 75 back into the end intake valve 61.

The cooling fixture 74 consists of a bowl 87 which is fastened to a spiral 88. The cold air will enter the bowl by means of the pipe 73 and will then be directed by the walls of the bowl upwardly and will pass between an inside and outside hollow cone 89 and 90 respectively, and will be directed thereby into the room.

We claim:

1. In a device of the class described, a food container, a box surrounding the same and spaced therefrom, vacuum cells and cooling coils arranged in groups in the space between the box and the container, each group consisting of a vacuum cell and a plurality of cooling coils, the coils of each group communicating with the cell of the same group and the cells of all groups communicating with each other, the space between the box and the container being filled with water surrounding the coils and the container and entering the vacuum cells, an air inlet, the cooling coils being connected thereto, a pump, a suction pipe on said pump communicating with the water filled space, a discharge pipe in said pump and an ejector in said discharge pipe and having communication with one of the vacuum cells.

2. In a device of the class described, a food container, a box surrounding the same and spaced therefrom, vacuum cells and cooling coils arranged in groups in the space between the box and the container, each group consisting of a vacuum cell and a plurality of cooling coils, the coils of each group communicating with the cell of the same group and the cells of all groups communicating with each other, the space between the box and the container being filled with water surrounding the coils and the container and entering the vacuum cells, an air duct, an air moistening device, the air duct communicating at one end with the atmosphere and at the other end with the air moistening device, all cooling coils communicating with said device, a pump, a suction member on said pump and in communication with the water filled space, a

discharge member on said pump extending upwardly therefrom and ending above the water level in the water filled space, a perforated closure on this end of the discharge member, an ejector in the discharge member 70 and in communication with one of the vacuum cells and a connection between the pump and the air moistening device adapted to deliver water from the pump to said device. 75

3. In a device of the class described, a food container, a box surrounding the same and spaced therefrom, vacuum cells and cooling coils arranged in groups in the space between the box and the container, each group consisting of a vacuum cell and a plurality of cooling coils, the cooling coils of each communicating with the vacuum cell of the same group and the cells of all groups communicating with each other, the space 80 between the box and the container being filled with water surrounding the coils and the container and entering the vacuum cells, an air duct, an air moistening device, the air duct communicating at one end with the 85 atmosphere and at the other end with the air moistening device, all cooling coils communicating with said device, a pump, a suction member on said pump and in communication with the water filled space, a discharge member on the pump and extending upwardly therefrom and ending above the water level in the water filled space, a perforated closure on this end of the discharge member, an ejector in the discharge member 90 and communicating with one of the vacuum cells, a connection between the pump and the air moistening device adapted to deliver water from the pump to said device, and a 95 check valve inserted in the air duct adapted to be opened by the suction created by the ejector and affecting the vacuum cells, the space between the box and the container, the cooling pipes, the air moistening device 100 and the air duct, said valve permitting upon 105 being opened fresh air to be forced along the path through said parts.

4. In a device of the class described, a food container, a box surrounding the same and spaced therefrom, vacuum cells and cooling coils in the space between the box and the container and arranged in groups 115 consisting each of a vacuum cell and a plurality of cooling coils, the coils of each group communicating with the cell of the same group and the cells of all groups communicating with each other, the space between the box and the container being filled with water, an air inlet pipe, an air moistening 120 device, said inlet pipe communicating at one end with the atmosphere and at the other end with the air moistening device, all cooling coils being in communication with said device, a pump, a suction member in said 125 pump and communicating with the water 130

filled space, a discharge member on said pump, an ejector in said discharge member and communicating with one of the vacuum cells, a check valve in the air inlet pipe and ¹⁰ adapted to be opened by the action of the ejector, and an air discharge pipe leading from the space between the box and the con-

tainer above the water level and adapted to conduct the cooled and moistened air out of said space to any desired place.

In witness whereof we have set hereunder our signatures.

HARRY A. STEINMEYER.
JOHN H. VOSS.
